JULES EUGÈNE MALIVERT, OF PARIS, FRANCE, ASSIGNOR TO SOCIÉTÉ ANONYME DES APPAREILS J. E. MALIVERT, OF PARIS, FRANCE.

REHEATING DEVICE FOR SOLDERING IRONS.

Application filed December 30, 1921. Serial No. 525,916.

To all whom it may concern:

Be it known that I, JULES EUGÈNE MALIVERT, a citizen of the French Republic, of 9 and 11 Rue du Télégraphe, Paris, France, have invented a Reheating Device for Soldering Irons, of which the following is a full, clear, and exact description.

This invention relates to a reheating device applicable to soldering-irons, soldering-lamps and various heating and lighting apparatuses operating with gasoline and other volatile fuels.

In these apparatuses, for instances, in soldering-irons is provided a device called gasifier where the fuel is vaporized by rise of temperature; this rise of temperature is obtained by the transmission of heat coming from the device where the combustion takes place, the gasifier being sufficiently near the said device.

This system operates in good conditions in most of the ordinary surrounding temperatures, but in cold weather, the gasifier may not be brought to a temperature sufficiently high for ensuring the proper vaporization of the gasoline.

This invention relates to a movable device, easy to put in position and remove, adapted to effect a reheating of the gasifier when it is necessary.

This device consists, substantially in a conduit which collects all or a part of the combustion products and brings them back into contact with the gasifier which is thus brought to a sufficient temperature.

The new device can be provided with a head capable of being set, so as to permit its application in the case of the apparatuses where the soldering-iron itself is capable of being set.

The head is circular and can rotate in a recess of corresponding shape, so that the chamber where the combustion of the gaseous products coming from the gasifier takes place is substantially closed and that the combustion products are forced to enter the reheating conduit.

In order that the invention may be understood, its application to a soldering-iron, is illustrated in the accompanying drawing, given by way of example only, in which:

Fig. 1 is an elevation of a soldering-iron provided with the new device.

Fig. 2 is a corresponding plan view.

Figs. 3 and 4 are two cross-sections re-

spectively on line A—A and B—B of Fig. 1.

Fig. 5 is a longitudinal section on line C—C of Fig. 2.

Fig. 6 is an elevation of the reheating device with a head capable of being set. 60

Figs. 7 and 8 are respectively side and plan views of Fig. 6.

Fig. 9 is a longitudinal section on an enlarged scale.

Fig. 10 is a section on line A—A of Fig. 9. 65

Figs. 11, 12 and 13 illustrate separately—the head capable of being set, in elevation, side and plan views.

As will be seen in the drawing, the soldering-iron to which the invention is applied, comprises a handle *a* or reservoir, an element *b* constituting the gasifier and a burner *c*. A removable armature *d* carries the soldering-iron proper *e*. 70

The reheating device is constituted, for instance, by a piece of sheet iron so shaped as to form a part *f* which fits on the rounded end of the armature *d*, a part *g* forming a conduit and a terminal portion *h* having two cheeks *i* laterally embracing the gasifier. 75

When the temperature is found to be sufficiently low for necessitating the putting in position of the reheating device, the securing bolt *j* is removed and the device is adapted on the soldering-iron, care being 80 taken to engage the cheeks *i* under the branches *k* of the armature of the soldering-iron. The bolt *j* is replaced and the fixation is completed by means of a pin *l*. 85

With this arrangement, the combustion products, instead of being evacuated directly in the atmosphere, are sent into the conduit *g* and pass around the gasifier *b*, as indicated by the arrows, in order to finally issue in the atmosphere. 90

For regulating the intensity of the reheating, the device is provided with a regulating element permitting to direct a greater or less portion of the combustion products on the gasifier. This element may consist for instance in a shutter *m*, rotating at *n*, on opening, more or less, this shutter, a portion of the combustion products can be directly evacuated in the atmosphere and the reheating can be controlled. 100

Instead of a rotating shutter, a rotating ring covering the orifices, a sliding shutter or any other appropriate arrangement may be used.

In the arrangement illustrated in Figs. 6 110

to 13, the removable armature *d* carrying the soldering-iron, above described, is replaced by a head capable of being set, shown in Figs. 11 to 18, also shown in section in Fig. 9 and which comprises two circular cheeks *d*¹ connected on a portion of their periphery by a cylindrical wall *d*², having a socket *d*³, adapted to receive the soldering-iron *e* which is secured by a screw *e*¹.

10 The reheating device is carried by an armature constituted by two cheeks *f*¹, perforated with holes so as to lighten them and facilitate their cooling. These cheeks are terminated by branches *k* and are connected 15 to each other by a metallic strip *o*, the ends *o*¹ *o*² of which are rounded concentrically with the head capable of being set, and having a round window *p*, Fig. 10, adapted to serve as a passage for the nose of the burner 20 and a rectangular window *q* through which the combustion products are brought back into the reheating conduit *g*. The latter is constituted by thin sheet iron plates forming 25 a conduit of square cross-section occupying the space between the two branches *k*. These sheet iron plates are terminated by cheeks *i* similar to those of the apparatus above mentioned.

15 The adjusting hinged shutter *m*, rotating at *n*, is controlled by a hand knob *m*¹.

From Fig. 9 it will be easily understood that the soldering iron may be given any desired inclination, it can be immobilized in any given position by tightening the nut *s*¹ 35 of a bolt *s* axially passing through the cheeks of the sheet iron plates capable of being set.

20 The shutter *m* occupying the position 1, illustrated in full lines, the combustion products follow the direction indicated by the arrows and thus come into contact with the gasifier *b*, which they reheat.

If it is desired to modify the action of the 25 reheating, the shutter *m* is turned to a greater or less extent, and if it is desired to omit this action the shutter is brought to the position 2 indicated in dotted lines; the gases then issues in the atmosphere.

30 The arrangements above set forth are given by way of example only; the forms, dimensions, materials employed and all detail arrangements may vary according to circumstances without departing thereby from the scope of the invention.

35 Claims:

1. A reheating device for soldering irons and similar apparatus, comprising a removable casing which is placed over the iron

when the temperature is low, said casing including a combustion chamber at its forward end, and a conduit leading from the combustion chamber to the gasifier and bringing back the combustion products to the gasifier. 60

2. A reheating device for soldering irons and similar apparatus, comprising a removable casing which is placed over the iron when the temperature is low, said casing including a combustion chamber at its forward end, and a conduit leading from the combustion chamber to the gasifier and bringing back the combustion products to the gasifier, and means for regulating the quantity of gas brought back to the gasifier. 65

3. A reheating device for soldering irons and similar apparatus, comprising a removable casing placed over the iron when the temperature is low, said casing including a combustion chamber at its forward end, and a conduit leading from the combustion chamber to the gasifier and bringing back the combustion products to the gasifier, and a shutter for bringing back the gases towards the gasifier or to throw them partly or entirely in the outside atmosphere. 75

4. A reheating device for soldering irons and similar apparatus, having a gasifier at a relative great distance from the iron proper, comprising a removable casing surrounding the iron and having a conduit parallel to the burner and ending at the gasifier. 80

5. A reheating device for soldering irons and similar apparatus having a gasifier at a relative great distance from the iron proper, comprising a removable casing surrounding the iron, and having a conduit parallel to the burner, and cheeks at the end of the conduit and surrounding the gasifier. 85

6. A reheating device for soldering irons and similar apparatus having a gasifier at a relative great distance from the iron proper, comprising a removable casing surrounding the iron, and having a conduit parallel to the burner and ending at the gasifier, and a regulating shutter on the conduit. 100

7. A reheating device for a soldering iron which can be moved in any direction having a removable casing surrounding the iron, and provided with a conduit adjusted to the casing and extending to the gasifier, said conduit bringing the heated gases to the gasifier. 105

The foregoing specification of my reheating device for soldering-irons signed by me this 15th day of December, 1921.

JULES EUGÈNE MALIVERT.
